UNITED STATES PATENT OFFICE.

ANDREW W. GRAHAM, OF BUFFALO, NEW YORK.

PROJECTILE.

1,219,724.

Specification of Letters Patent. Patented Mar. 20, 1917.

Application filed May 15, 1916. Serial No. 97,619.

To all whom it may concern:

Be it known that I, ANDREW W. GRAHAM, a citizen of the United States of America, residing at Buffalo, in the county of Erie 5 and State of New York, have invented certain new and useful Improvements in Projectiles, of which the following is a specification.

This invention relates to projectiles and 10 has special reference to a projectile adapted to be used in repelling attacks of air craft such as aeroplanes and balloons.

It is a well known fact that rifle fire is 15 ineffective on air craft when they are flying at the usual altitude at which such craft operate in war times. It is also well known that owing to the uncertainty of the distance between such craft and the gun from which shrapnel is fired the latter is ineffective.

20 The principal object of the present invention is to provide an improved form of projectile which will discharge a volley of bullets when it has reached a certain height below the craft which it is desired to attack, 25 the bullets being directed toward the object instead of scattered uncertainly around as in the case of shrapnel.

Another important object of the invention 30 is to provide a projectile capable of discharging two or more volleys of such bullets at different points in its flight.

With the above and other objects in view, 35 as will be hereinafter apparent the invention consists in general of certain novel details of construction and combinations of parts hereinafter fully described, illustrated in the accompanying drawings, and specifically claimed.

In the accompanying drawings, like characters of reference indicate like parts in the 40 several views, and:

Figure 1 is a longitudinal section through the forward part of a projectile constructed in accordance with this invention;

45 Fig. 2 is a section on the line 2—2 of Fig. 1;

Fig. 3 is a section on the line 3—3 of Fig. 1.

In the present embodiment of the invention 50 there is disclosed the forward portion of a projectile which includes the body or base portion 10 and the nose or point portion 11. These two parts are separately constructed and are connected in any suitable

manner which may be desired. For instance, 55 bolts 13 may be used for connecting the two parts, although this is to be taken as merely typical of a form of connection. The part 11 is provided with a plurality of series of openings each of which includes a barrel 60 portion 14 which is preferably rifled and a chamber 15 for the reception of a rifle cartridge 16 of the ordinary type. These openings are arranged concentrically about the axis of the projectile and may lie either 65 parallel to such axis or diverge forwardly therefrom as desired. The portion 10 of the projectile engages the nose 11 about its periphery and is recessed as at 17. From this recess extends a channel 18 and 70 extending rearwardly from this channel are openings 19 corresponding in number and alined with the openings 14. In this portion of the projectile there is also provided a centrally disposed opening 20. 75

At 21 is a sleeve which is revolvably mounted in the opening 20 and carries on its forward end a disk 22 which is seated in the recess 17 and is provided with annular portions 23 fitting in the channel 18. This 80 disk and the portions 23 are provided with slots 24 and the slots in one series are longer than the slots in the adjacent series and are staggered in relation thereto. Slidable in the openings 19 are firing pins 25 and plugs 85 26 close the rear ends of said openings 19. Between these plugs and the rear ends of the firing pins 25 are coil springs 27. The forward ends of the firing pins are normally held against the solid portions of the parts 90 23 but, when the disk 22 is revolved the slots 24 are brought into alinement with the openings 19 so that the firing pins are released and are projected through the slots against the bases of the firing caps of the cartridges 95 16. By reason of the staggered relation of the slots in the different series these series are set off successively, the firing pins being successively released. Moreover, it is to be noted that the elongations of the slots in one 100 series over the slots in the other series permits movement of the disk 22 after the first series is fired.

In order to effect movement of the disk 22 there is provided a shaft 28 which has its forward end screwed firmly into the portion 11 of the projectile and on this shaft is mounted a gear 29 which is fixed to the sleeve 21,

Mesing with this gear 29 is a gear 30 which is carried by a drive shaft 31. This drive shaft is connected to any suitable timing mechanism which I may see fit to adopt and which forms no part in its specific construction of the present invention since a variety of forms are now known for the purpose and may be adapted for use in this connection.

- 10 In the operation of the device, the projectile is fired in the usual manner. Suppose the aeroplane should be estimated as at a distance of 5,000 ft. The timing mechanism may be so set in the usual manner 15 that the disk 22 will be turned at, say, 3,000 ft. to release the first set of firing pins and thereby fire the first set of cartridges. At, say, 4,000 ft. the disk will have turned sufficiently to release the second set of firing 20 pins and a second volley will be fired. It is to be noted that not only will these projectiles or bullets have the velocity due to the movement of the main projectile itself but the charge in the cartridge will add additional velocity thereto so that the main projectile carries the bullets to such a point 25 that they will be effective against an aeroplane or the like.

Moreover, it is to be noted that the shell 30 itself may be an explosive shell.

There will thus be produced the effect of repeated volleys of bullets against the air craft fired at such distances as to render them thoroughly effective.

35 There has thus been provided a simple and efficient device of the kind described and for the purpose specified.

It is obvious that many minor changes 40 may be made in the form and construction of the invention without departing from the material principles thereof. It is not therefore desired to confine the invention to the exact form herein shown and described but it is wished to include all such 45 as properly come within the scope claimed.

Having thus described the invention, what is claimed as new, is:—

1. A projectile including a forward portion provided with a series of cartridge receiving openings and having a hollow base, 5 a series of spring-pressed firing pins mounted in said base, and means normally holding said pins retracted and arranged to move and release successive pins.

2. A projectile including a forward portion provided with a series of cartridge receiving openings and having a hollow base, a series of spring-pressed firing pins mounted in said base, a disk revolubly mounted in said base and normally closing said openings, said disk having a series of openings arranged to be moved into alinement with the openings to permit movement of the firing pins.

3. A projectile including a forward portion provided with a plurality of concentric rows of forwardly directed rifled openings adapted to receive cartridges, a revoluble disk mounted in the projectile and provided with similar rows of openings adapted to 60 register with the first openings, and spring-pressed firing pins normally bearing against said disk in alinement with the rifled openings.

4. A projectile including a forward portion provided with a plurality of concentric rows of forwardly directed rifled openings adapted to receive cartridges, a revoluble disk mounted in the projectile and provided with similar rows of openings adapted to 70 register with the first openings, and the openings in one row being staggered with respect to the openings in the adjacent row.

In testimony whereof I affix my signature in presence of two witnesses.

ANDREW W. GRAHAM.
